UNITED STATES PATENT OFFICE.

DONALD McLEOD, OF NEW YORK, N. Y.

DESIGN FOR A DISPLAY STAND.

Application filed July 27, 1926. Serial No. 18,495. Term of patent 3½ years.

To all whom it may concern:

Be it known that I, DONALD McLEOD, a citizen of the United States, residing at New York city, in the county and State of New York, have invented a new, original, and ornamental Design for a Display Stand, of which the following is a specification, reference being had to the accompanying drawing, forming part thereof.

The figure is a perspective view of a display stand, showing my new design.

I claim:—

The ornamental design for a display stand, as shown.

DONALD McLEOD.
